CLAIM

The ornamental design for a humidifying device, as shown and described.

DESCRIPTION

FIG. 1 is an isometric view of the humidifying device showing my new design;

FIG. 2 is a front elevational view thereof;

FIG. 3 is a top plan view thereof;

FIG. 4 is a bottom plan view thereof;

FIG. 5 is a left elevational view thereof;

FIG. 6 is a right elevational view thereof; and,

FIG. 7 is another isometric view thereof.
